UNITED STATES PATENT OFFICE.

DEL ROY F. FOWLER, OF MELROSE PARK, PENNSYLVANIA, ASSIGNOR TO FREDERICK P. WOLL, OF PHILADELPHIA, PENNSYLVANIA.

PADDING-BANDAGE.

1,332,550.

Specification of Letters Patent.

Patented Mar. 2, 1920.

Application filed October 4, 1918. Serial No. 256,927.

To all whom it may concern:

Be it known that I, DEL ROY F. FOWLER, a citizen of the United States of America, residing in Melrose Park, in the county of 5 Montgomery and State of Pennsylvania, have invented certain new and useful Improvements in Padding-Bandages, of which the following is a true and exact description, reference being had to the accompanying 10 drawings, which form a part thereof.

My invention relates to the makeup of padding bandages especially intended and adapted for use in wrapping splints used for surgical operation and for wrapping 15 dressed members.

Heretofore unabsorbent cotton batting or bats of other fibrous materials have been used for such purposes, but they have proved unsatisfactory in use because such bats have 20 but little permanency in form and little tensile strength, and, therefore, involve some difficulty in proper application and are not adapted for reuse. The object of my invention is to provide a fibrous batting suitable for such uses as I have indicated, which 25 will have greater permanence and rigidity of form and greater tensile strength, and hence can be better applied in use and be also capable of reuse.

30 The nature of my invention will be best understood as described in connection with the drawings in which it is illustrated and in which—

Figure 1 is a cross sectional view of the 35 central core of my padding bandage.

Fig. 2 is a cross section of the non-absorbent fibrous batting used in the construction of my padding bandage.

Fig. 3 is a cross section through the complete padding bandage, and

Fig. 4 a longitudinal section on the line 4—4 of Fig. 3.

A is the core of the padding bandage and is made up preferably of a long and relatively narrow sheet of paper, thin enough to be readily flexible and stiff enough to afford a bracing and stiffening element to the

bandage as a whole. I prefer to use paper as the material for this core not only because it would be quite flexible longitudinally and sufficiently stiff laterally, but also because of its good qualities as a non conductor of heat, but other material such as a fairly stiff woven fabric can be used in place of it. B is the batting made up of non-absorbent fibrous material, preferably cotton, and formed with a central portion B' of uniform thickness and tapered edges B² and B³. In making up my padding bandage the batting is folded around the core 60 A, as shown in Fig. 3, the tapered ends of the batting being folded down upon the paper and upon each other, so that the thickness of the fibrous material on both sides of the core will be approximately uniform. C indicates the padding bandage.

It will be obvious that my padding bandage, constructed as above described, will be entirely flexible in a longitudinal direction, reasonably stiff laterally, and that it can 70 be readily applied as a wrapping for splints or other dressed members and that it has sufficient permanency of construction to enable it to be reused.

Having now described my invention, what 75 I claim as new and desire to secure by Letters Patent, is:

1. A padding bandage consisting of a long, narrow strip formed of a central core of relatively stiff and strong material in 80 combination with and inclosed by an outer surface made up of an unabsorbent fibrous bat having tapered edges folded about the core and with its tapered edges lapped on one side of the core.

2. A padding bandage consisting of a long, narrow strip formed of a central core of relatively stiff and strong paper in combination with and inclosed by an outer surface made up of an unabsorbent fibrous bat having tapered edges folded about the core and with its tapered edges lapped on 85 one side of the paper core.

DEL ROY F. FOWLER.
